United States Patent Office

Des. 179,375
Patented Dec. 11, 1956

179,375

TIRE

Henry D. Bishop, Detroit, and Edward H. Wallace, Grosse Pointe, Mich., assignors to United States Rubber Company, New York, N. Y., a corporation of New Jersey

Application January 25, 1955, Serial No. 34,191

Term of patent 14 years

(Cl. D90—20)

Fig. 1

Fig. 1 is a side elevational view of a tire showing our new design;

Fig. 2 is an enlarged sectional and fragmentary perspective view of the tire showing our new design;

Fig. 3 is a partial sectional view taken on the line III-III of Fig. 1;

Fig. 4 is a sectional view taken on the line IV-IV of Fig. 3; and

Fig. 5 is a sectional view taken on the line V-V of Fig. 3.

The characteristic feature of the tire design disclosed resides in the combination in a sidewall of a tire of a relatively narrow, circumferentially extending, white band located intermediate the bead and tread of the tire and separated from the bead and the tread of the tire by substantially wider, relatively dark sidewall areas extending respectively from the inner circumference of said white band to said bead and from the outer circumference of said white band to said tread, and circumferentially

spaced, rib-like elements on said dark sidewall areas extending radially inwardly and outwardly from adjacent the edges of said white band toward said bead and tread respectively, substantially as shown.

We claim:

The ornamental design for a tire, substantially as shown and described.
